UNITED STATES PATENT OFFICE.

SIMON SNYDER, OF MUNCY, PENNSYLVANIA, ASSIGNEE TO SPROUT, WALDRON & CO.,
OF MUNCY, PENNSYLVANIA, A CORPORATION OF PENNSYLVANIA.

GRINDING MILL.

Application filed March 28, 1923. Serial No. 628,368.

To all whom it may concern:

Be it known that I, SIMON SNYDER, a citizen of the United States, residing at Muncy, in the county of Lycoming and State 5 of Pennsylvania, have invented certain new and useful Improvements in Grinding Mills; and I do hereby declare the following to be a full, clear, and exact description of the invention, such as will enable others skilled 10 in the art to which it appertains to make and use the same.

This invention relates to milling machines and more particularly to grinding mills, in which opposed grinding plates or disks are 15 used to grind wheat or other grain.

The object of my invention is to provide a milling machine which may be quickly disassembled for the purpose of exposing the interior to convenient inspection and permitting ready access to the grinding plates or disks for adjustment or removal and replacement, without requiring a complete disassembly, disarrangement or loosening of fixed parts, and without necessitating the 25 removal or displacement of the drive shaft from its bearings.

A further object is to provide a novel two-part, separable shaft, in connection with milling machines, one part of which may be 30 readily disconnected from the other part without disturbing or displacing the latter when the machine is partially disassembled. Thus, one end of the machine, through which when assembled, the united shaft extends, may be left wholly intact, while the other end is unbolted and removed from place.

Simplicity of design and arrangement of parts, economy in time and labor afforded 40 for repair and adjustment, accessibility and maximum strength and durability, are further desiderata which have been borne in mind in the production of my improved milling machine.

The invention will first be hereinafter more particularly described, with reference to the accompanying drawings, which are to be taken as a part of this specification and then pointed out in the claims at the 45 end of the description.

In said drawings, Fig. 1 is a side elevation of the assembled milling machine;

Fig. 2 is an end elevation of the same, taken on the line 2—2 of Fig. 1;

Fig. 3 is a sectional side elevation of the

assembled machine shown in Fig. 1, taken on a vertical plane through its axis, the shaft being shown in elevation;

Fig. 4 is a fragmentary elevational view, partly in section, of the separable drive 60 shaft and bearings;

Fig. 5 is an elevation of the shaft taken at right angles to Fig. 4, the bearings being omitted; and

Fig. 6 is a fragmentary elevational view 65 of the shaft illustrating a modification.

Referring to the drawings, in which like reference numerals are used to denote corresponding parts throughout the several views, 7 denotes a cast iron or other metal 70 supporting base, to which the superstructure of the mill is rigidly bolted. A feed outlet or discharge passage 8 (preferably of inverted frusto-conical shape), is formed or provided in said base so as to extend vertically therethrough at one end. A chute (not shown) may be connected at the lower extremity of said outlet passage to convey the comminuted material to any desired point. 80

A drum-like metal casing which is closed at the top but open at the bottom and formed by oppositely related, separable sections 9 and 10, is rigidly bolted to the base 7 with the constricted open bottom of the casing in direct communication with the feed outlet passage 8. Marginal flanges are formed at the lower extremities of the sections through which bolt holes, corresponding with similar holes in the base 7, are 90 provided to receive fastening bolts. Corresponding radial apertured lugs 11 and 12, are also formed on the outer peripheral margins of sections 9 and 10, respectively, through which suitable bolts are passed to 95 firmly secure the two sections together.

A circular feed inlet opening 13 is formed through the vertical wall of the section 10, and a feed hopper 14 is mounted by suitable clamping means at the top of the section in 100 line with said opening. A revoluble agitator 15, keyed to a driven shaft 16, (to be hereinafter more particularly referred to) is located within the lower portion of said hopper between its tapering walls. 105

An oblong, open-sided chute 17 is suitably clamped or screwed into place against the vertical wall of section 10 of the casing with its open side toward and extended below the inlet opening 13, the open end of said chute 110

registering with the lower opening in the hopper, and the closed end thereof providing an inclined bottom for the vertical feed passage 18 thus formed in communication with said inlet opening.

A regulating closure plate 19, movable inwardly and outwardly between suitable guide-ways by means of an adjusting screw bolt 20, is provided at the base of the hopper to control the amount of material released therefrom into the feed passage.

Alined shaft journal boxes 21 and 22 are securely bolted at opposite sides of the casing to sections 9 and 10 respectively, by means of suitable yoke members 23 and 24, which are preferably formed integral therewith as shown. An end journal box 25 is also provided in alinement with said first mentioned boxes, which is rigidly supported by an upright bracket or standard 26 firmly bolted to the base 7. Removable cover plates or caps are provided for each of these journal boxes.

A separable drive shaft formed by co-operable and complementary parts 27 and 28, is journaled in radial and end-thrust ball bearings 29 provided in each of the journal boxes 21, 22 and 25. An ordinary belt pulley 30 is keyed to part 27 of the drive shaft, and is driven by an endless belt extending therefrom to a revolving element on a power unit (not shown). A strap pulley 31 is rotatable with the part 28 of the drive shaft, by means of an elongated groove or keyway 28^a formed in the shaft into which the free end of a set screw 31^a extending radially through said pulley projects to key the pulley to the shaft, while permitting the pulley to move longitudinally thereof. From the pulley 31, an endless strap 32 is extended over a driven pulley 33 keyed to one end of the agitator shaft 16. Suitable bearings are formed or provided at the top of sections 9 and 10 of the casting to support this shaft.

Enclosed within the casing are opposed grinding disks or plates 34 and 35, the plate 34 being securely bolted to and revoluble with a hubbed disk 36 keyed to the part 28 of the drive shaft, while the plate 35 is stationary and rigidly bolted to the inner vertical wall of section 10 of the casing, with its eyelet or central opening corresponding with the inlet opening 13 in said section. Keyed to the part 28 of the drive shaft and located axially within the inlet passage 13, is a rotatable feed promoting member or conveyor 37 having inwardly tapering triangular blades 38 at one end and flat-sided oblong blades 39 at the other end projecting radially therefrom. The tendency of the triangular blades is to urge the feed between the grinding plates 34 and 35 as it falls from the hopper into the feed

passage 18. It will be observed by reference to Fig. 3 of the drawings that the agitator 15 essentially corresponds in structure with the rotatable conveyor 37.

Referring particularly to Figs. 3, 4 and 5, it will be observed that the drive shaft 70 which extends entirely through the casing with its axis corresponding with the axis of the inlet opening 13, is formed as mentioned above, in two parts 27 and 28. These two parts are preferably united at a point exterior to the casing and for convenience, may be joined as shown, within journal box 22.

One end of the fixed part 27 of the shaft is adapted to threaded engagement with a suitable locking nut within the journal box 25, while its other end is formed with a tongue 27^a adapted to fit snugly within an elongated slot or recess 28^a formed by the opposing bifurcated end of the part 28 of the shaft, thus effecting a male and female connection between these two parts. The opposing end of the shaft part 28 is also formed with a chamber or axial bore 28^b within which a helical spring 40 is housed.

The united ends of parts 27 and 28 of the shaft are enclosed by a threaded and shouldered guide sleeve or collar 41, over which one of the bearings 29 is fitted to bear against the shoulder thereon, a suitable nut being screwed thereagainst to hold the sleeve in place. Said sleeve is provided with a stout diametrical pin 42 extended therethrough, over which the bifurcated end of the part 28 of the shaft is slipped (as illustrated in Figs. 4 and 5), and against which the end of the tongue on the part 27 may bear. The spring 40 also bears tensionably at one end against said pin and at the other end against the end wall of the chamber or bore 28^b, tending to move the part 28 outwardly from co-operative connection with the part 27 of the shaft.

This spring permits the rotatable grinding plate 34 to yield or move away from the opposing stationary plate 35, thus aiding their separation when pressure against the free end of the part 28 of the shaft is relieved for the purpose of withdrawal, and serves also as a check to prevent the plates 34 and 35 from coming into contact when the part 28 is replaced and set to operative position.

The opposite end of the part 28 of the shaft, which is supported in journal box 21, is likewise bifurcated to slidably fit over a diametrical pin similarly provided in a sleeve 41^a corresponding structurally to the sleeve 41, and a bearing 29 is fitted thereover in like manner.

An end-bearing 43 is provided in the extended cover or cap of journal box 21 to non-yieldingly bear against the free end of the united drive shaft, to hold the two parts

in association and prevent outward movement of the part 28 beyond a predetermined point. A hand wheel 44 having a threaded shank extending through the cap of the journal box 21 to press against the bearing 43, is provided for laterally adjusting the shaft.

By reference to Fig. 3 it will be observed that the driven shaft 16 is also constructed in two parts, a male and female connection being established therebetween in order that one part may be removed without disturbing the other part.

Instead of the open-ended slot-and-pin connection between the outer end of the shaft section 28 and the sleeve 41^a whereby they are caused to rotate together, the end of the shaft may be square or polygonal in cross-section and inserted in a correspondingly shaped bore or opening through the sleeve; this modification being shown in Fig. 6 of the drawings, and a similar connection may be provided between the inner ends of the two shaft sections 27 and 28, respectively, within the sleeve 41, to cause the sleeve to rotate with the shaft while permitting a limited longitudinal movement of the section 28, and adapting it to be removed with the removable casing member.

The "knock-down" operation of my improved mill grinder is effected as follows:

The endless strap 32 is disconnected and pulley 33 is removed, together with one part of separable shaft 16. The holding bolts through lugs 11 and 12 on sections 9 and 10, respectively, are next removed and also the base fastening bolts for section 9. The entire section may then be withdrawn from section 10, carrying therewith part 28 of the drive shaft with associated elements, leaving section 10 and associated parts undisturbed. The grinding plates will thus be exposed to view and will be readily accessible for repair. If desired, the various parts of the machine which are bolted or otherwise secured to section 9, may be severally disconnected and removed. When it is desired to remove and replace the grinding plates, section 9 is unbolted and drawn far enough from section 10 to permit disengagement of parts 27 and 28 of the shaft and the set screw 31^x in pulley 31 is removed so that the pulley may move freely beyond the extremities of the key-way 28^x in the shaft. The part 28 of the shaft, with disk 36 and grinding plate 34 may then be drawn out without removing the journal box 21 or associated parts. The machine is re-assembled by a reversal of this operation, the part 28 of the shaft being re-united with its co-operating part 27 by revolving the former until its bifurcated end slips over the cross-pin in sleeve 41, whereupon the several casing bolts, pulley 33 with removed

part of shaft 16 and endless strap 32 are replaced to render the machine again operable.

Having thus described my invention, what I claim as new and desire to secure by Letters-Patent of the United States is:

1. The combination, in an attrition mill, of a casing for the grinder composed of two members, one removably secured to the other and to a supporting base, and each having an open-ended bearing box supported on the outer side thereof, an annular anti-friction bearing in each of said boxes including a sleeve on the grinder shaft rotatable therewith and carrying the rotatable member of the bearing, a third bearing mounted on said base in alinement with the first named bearings, a sectional shaft journaled in said bearings, the section carried by the removable casing member projecting through the fixed casing member into the bearing box carried by the latter member, and the other section having one end journaled in said third bearing and the other end fitted in the sleeve within the bearing box carried by said fixed casing member, and means on the adjacent ends of said shaft sections within the sleeve thereon whereby both shaft sections and the sleeve are caused to rotate together while permitting a limited longitudinal movement of the shaft section which extends through the casing and adapting it to be disconnected and removed with the removable casing member without disturbing the fixed casing member and the parts associated therewith.

2. The combination, in an attrition mill, of a casing for the grinder composed of two members, one removably secured to the other and to a supporting base, and each having an open-ended bearing box supported on the outer side thereof, an annular radial and end-thrust anti-friction bearing in each of said boxes including a sleeve on the grinder shaft rotatable therewith and carrying the rotatable member of the bearing, a third bearing mounted on said base in alinement with the first named bearings, a sectional shaft journaled in said bearings, the section carried by the removable casing member projecting through the fixed casing member into the bearing box carried by the latter member, and the other section having one end journaled in said third bearing and the other end fitted in the sleeve within the bearing box carried by said fixed casing member, and means on the adjacent ends of said shaft sections within the sleeve thereon whereby both shaft sections and the sleeve are caused to rotate together while permitting a limited longitudinal movement of the shaft section which extends through the casing and adapting it to be disconnected and removed with the removable casing

member without disturbing the fixed casing member and the parts associated therewith.

3. The combination, in an attrition mill, of 5 a casing for the grinder composed of two members, one removably secured to the other and to a supporting base, and each having an open-ended bearing box supported on the outer side thereof, an annular anti-friction 10 bearing in each of said boxes including a sleeve on the grinder shaft rotatable therewith and carrying the rotatable member of the bearing, a third bearing mounted on said base in alinement with the first named bearings, a sectional shaft journaled in said bearings, the section carried by the removable casing member projecting through the fixed casing member into the bearing box carried by the latter member, and the other section 15 having one end journaled in said third bearing and the other end fitted in the sleeve within the bearing box carried by said fixed casing member, and inter-engaging means on the adjacent ends of said shaft 20 sections within the sleeve thereon whereby both shaft sections and the sleeve are caused to rotate together while permitting a limited longitudinal movement of the shaft section which extends through the casing and adapting 25 it to be disconnected and removed with the removable casing member without disturbing the fixed casing member and the parts associated therewith; said inter-engaging means comprising an open-ended slot 30 at the end of one shaft section, a cross-pin in said slot carried by the sleeve, and a tongue projecting from the adjacent end of the other shaft section into said slot.
4. The combination, in an attrition mill, of 35 a supporting base having a discharge opening therein, a casing for the grinder composed of two members arranged over said opening, one removably secured to the other and to said supporting base and each having an open-ended bearing box supported 40 on the outer side thereof, an annular anti-friction bearing in each of said boxes, each including a sleeve on the grinder shaft rotatable therewith and carrying the rotatable member of the bearing, a sectional shaft journaled in said bearings, the section carried by the removable casing member projecting through the fixed casing member into the bearing carried by the latter member, the other section having one end journaled 45 in said third bearing and the other end journaled in the bearing carried by said fixed casing member, the latter bearing including a sleeve within which the adjacent ends of said shaft sections are slidably secured so as to cause them to rotate together and the sleeve to rotate therewith while permitting a limited longitudinal movement of the shaft section which is carried by the removable casing member and the removal thereof with said removable casing member without disturbing said fixed casing member and the parts associated therewith.
5. A knock-down attrition mill comprising 50 a stationary and a removable casing member enclosing the grinding plates, said casing members carrying on the outer sides thereof alined shaft bearings, a sectional shaft having one section journaled in said 55 base in alinement with the first named bearings, and means on the adjacent ends of said shaft sections within the sleeve thereon whereby both shaft sections and the sleeve are caused to rotate together while permitting a limited longitudinal movement of the shaft section which extends through the 60 shaft section which

casing and adapting it to be disconnected and removed with the removable casing member without disturbing said fixed casing member and the parts associated therewith.

5. In an attrition mill, two casing members mounted on a supporting base, one fixed and the other removable, the fixed member carrying a grinding plate and having a feed opening therein and a hopper mounted thereon provided with a chute arranged to discharge into said opening, a bearing supported upon the outer side of each casing member, a sectional shaft journaled in said bearings, one section thereof being carried by said removable casing member and extending through the other casing member into the bearing supported thereon, the other section of said shaft having one end journaled in the bearing carried by said fixed casing member and the other end journaled in a third bearing spaced from the last named bearing, the adjacent ends of the two sections being secured within a sleeve of the bearing carried by said fixed casing member so as to cause them to rotate together and cause the sleeve to rotate therewith while permitting the section carried by the removable casing member to be disconnected and removed without disturbing the fixed casing member and the parts associated therewith.

6. The combination, in an attrition mill, of a casing for the grinding plates composed of a fixed member and a removable member arranged side by side and having a feed hopper mounted thereon, said members each having a shaft bearing supported on the outer side thereof, a third bearing arranged in alinement with the bearing carried by said fixed member, a sectional shaft journaled in said bearings, one section being carried by the removable casing member and projecting through the fixed casing member into the bearing carried by the latter member, the other section having one end journaled in said third bearing and the other end journaled in the bearing carried by said fixed casing member, the latter bearing including a sleeve within which the adjacent ends of said shaft sections are slidably secured so as to cause them to rotate together and the sleeve to rotate therewith while permitting a limited longitudinal movement of the shaft section which is carried by the removable casing member and the removal thereof with said removable casing member without disturbing said fixed casing member and the parts associated therewith.

7. A knock-down attrition mill comprising a stationary and a removable casing member enclosing the grinding plates, said casing members carrying on the outer sides thereof alined shaft bearings, a sectional shaft having one section journaled in said

bearings and the other section journaled in one of said bearings and a third bearing in alinement therewith, the adjacent ends of said shaft sections being connected so 5 that they are caused to rotate together while permitting a limited longitudinal movement of one section independently of the other and adapting the movable shaft section to be removed and replaced with the 10 removable casing member without disconnecting or disarranging the parts associated therewith or the parts associated with the stationary casing member.

8. A knock-down attrition mill comprising 15 a stationary and a removable casing member enclosing the grinding plates, said casing members carrying on the outer sides thereof alined shaft bearings, a third bearing in alinement with one of said bearings, a sectional shaft journaled in said bearings, one section being carried by the removable casing member, interengaging means on the adjacent ends of the sections whereby they are caused to rotate together while permitting a limited longitudinal movement of one section to disconnect it from the other section and permit its removal with said removable casing member, a second sectional shaft journaled in 20 bearings mounted on said casing, one section being removable with said removable casing member, a hopper having a down spout or conduit leading into an opening in the stationary grinding plate, a rotary feeding 25 and stirring device on each sectional shaft, one arranged within the opening through the stationary grinding plate and the other within the feed hopper, and a driving connection between the two shafts.

40 9. In an attrition mill having a base and grinder-plate housing, a sectional grinder actuating shaft journaled in bearings supported on said base and housing, the inner ends of the two shaft sections being fitted 45 in a sleeve forming a part of one of said bearings, said sleeve having a cross-pin therein and one end of one shaft section within said sleeve having a tenon thereon in alinement with said pin, the adjacent end 50 of the other shaft section having an oblong open-ended slot therein slidably fitted on said pin and tenon, thereby causing the sleeve and the two shaft sections to rotate

together for actuating the grinder while permitting a limited longitudinal movement of 55 the shaft section having the slotted end and adapting it to be adjusted longitudinally and disconnected from the other shaft section and the sleeve without removing a bolt or screw. 60

10. In a knock-down grinding mill, having 65 grinder-plates and a housing therefor, a revoluble grinder actuating sectional shaft, adjacent ends thereof having a slot and tongue connection, and a coupling sleeve enclosing the united ends of the shaft, having a cross-pin therethrough adapted to fit within the slot of one of the sections, and alined with the connecting tongue on the adjacent section against which the latter may 70 non-yieldingly press.

11. In a knock-down grinding mill, having 75 grinder-plates and a housing therefor, a revoluble grinder actuating sectional shaft, one end of one section thereof being bifurcated and the adjacent end of the other section having a tongue adapted to fit therebetween, a coupling sleeve enclosing the united sectional ends of the shaft having a cross-pin therethrough adapted to fit transversely within the bifurcated end of one section adjacent to and parallel with the free end of the tongue on the other section against which the latter may non-yieldingly press. 80

12. In a knock-down grinding mill, having 85 grinder-plates and a housing therefor, a revoluble grinder actuating sectional shaft, one end of one section thereof having an axial chamber and an elongated bifurcation 90 formed therein, and the adjacent end of the other section having a tongue adapted to engage with said bifurcated end, a coupling sleeve enclosing the united sectional ends of the shaft having a cross-pin therethrough 95 adapted to fit transversely within the bifurcated end of one section adjacent to and parallel with the free end of the tongue on the other section, and a spring housed within the axial chamber in the first mentioned section adapted to press against the cross-pin in said sleeve and tending to force the two sections apart. 100

In testimony whereof I affix my signature.

SIMON SNYDER.
